M. MACDONALD

AUTOGRAPHIC REGISTER

Filed Jan. 5, 1923

FIG. 1.

FIG. 2.

FIG. 3.

FIG. 4.

INVENTOR:
Murdock Macdonald
BY:
R. Merle,
ATTORNEY.

UNITED STATES PATENT OFFICE.

MURDOCK MACDONALD, OF CLEVELAND, OHIO.

AUTOGRAPHIC REGISTER.

Application filed January 5, 1923. Serial No. 610,742.

To all whom it may concern:

Be it known that I, MURDOCK MACDONALD, a citizen of the United States, resident of Cleveland, county of Cuyahoga, and State 5 of Ohio, have invented new and useful Improvements in Autographic Registers, of which the following is a specification, the principle of the invention being herein explained and the best mode in which I have 10 contemplated applying that principle, so as to distinguish it from other inventions.

My invention relates to autographic registers, its object being to provide a register simple in construction, economical of manufacture and which will efficiently perform its 15 functions.

Said invention consists of means herein-after fully described and particularly set forth in the claims.

More particularly, the object of my invention is to provide means whereby one of a multiplicity of superposed strips wound upon a single roller, may be segregated from the other strips for the purpose of separate 25 filing or retention.

This object I attain by providing a secondary roller upon which this segregated strip is wound after it has been unwound from the main roller, such secondary roller being 30 mounted and cooperating with the main roller in the manner hereinafter fully disclosed.

The annexed drawing and the following description set forth in detail certain means 35 embodying my invention, the disclosed means, however, constituting but one of various ways in which the principle of my invention may be applied.

In said annexed drawing:

Fig. 1 represents a plan of a register embodying my invention, showing the top or cover member broken away.

Fig. 2 represents a longitudinal vertical section of said device.

Fig. 3 represents a plan of the main roller detached from the frame and showing the multiplicity of strips wound thereon.

Fig. 4 represents a transverse section, showing the rollers in elevation, and taken 50 upon the plane indicated by line IV—IV in Fig. 2.

The illustrated embodiment of my invention comprises a suitable frame consisting of two side members 1—1, Figs. 1 and 4, connected transversely by suitable tie-rods 2, 2'

and 2''. These side members are each formed with two parallel slots 3 (vertical as shown) open at the upper end, Fig. 2.

The lower ends of these slots form bearings for the end portions of a spindle 4 of 60 the main roller 5. The opposite sides of this roller are provided with cylindrical bosses 6—6 upon each of which is fixedly secured a driving wheel 7, such wheels being of equal diameter.

Also seated in said slots 3—3 are the end portions of a spindle 8 of a secondary roller 9, Fig. 4, and on these end portions and adjacent to the opposite sides of said roller 9 are secured two pinions 10—10. These 70 pinions rest upon the driving wheel 7, frictionally engage the periphery thereof, and said wheels and pinions are made of material suitable for providing such frictional engagement as will cause the roller 9 to 75 rotate when the wheels 7 are rotated. To this end the wheels 7—7 may be made of steel and the pinions 10—10 of rubber.

One end of the spindles 4 and 8 respectively is extended laterally, as shown in Fig. 80 4, and each such end is provided with a thumb piece, 11 and 12 respectively.

A platen 13 preferably inclined downwardly and forwardly, as shown in Fig. 2, is supported by the side members 1—1 transversely and in front of the main roller 5. The lower portion of this platen is provided 85 with a knife 14 by means of which the forms of the strip may be severed as is usual.

A suitable movable or hinged cover 15 is 90 provided as will be understood.

As shown in Fig. 2, the tie-rod 2' is mounted between the inner end of the platen 13 and the roller 5 and the tie-rod 2'' is mounted at the front of the frame and below 95 the front end of the platen. Rollers 16 and 17 are mounted respectively upon these two tie-rods.

The roller 5 is preferably made in two sections divided as at 18, Fig. 4, one wheel 7 100 being hence attached to each section.

A suitable carbon sheet receptacle 19 is provided from which carbon sheets 20 may be fed transversely across the platen as is customary and as will be readily understood 105 by those skilled in the art.

A multiplicity of strips of paper, the upper one of which is usually provided with a printed form, are wound in superposed relation upon a cardboard tube 21, Fig. 4, 110

into which the two portions of the roller 5 are inserted from opposite sides and frictionally held thereon.

The upper or secondary roller 9 is provided with a slot 22 intersecting its cylindrical surface and parallel with the roller's axis as shown in Fig. 2.

The strips pass from the roller 5 over the roller 16 and then over the platen 13, as shown in said Fig. 2, the carbon sheets 20 being inserted between each two adjacent sheets. The lowermost sheet 23 passes from the end of the platen 13 downwardly around the roller 17, around the roll of strips on the roller 5 and up to the roller 9, its end being inserted in the slot 22.

As the sheets are pulled over the platen by hand, as is customary in this type of registers, the roller 5 is rotated, which action effects the rotation of the wheels 7. The rotation of these wheels effects the rotation of the pinions 10 and hence of the roller 9, the direction of rotation being indicated by the arrows in Fig. 2. Such rotation of the roller 9, therefore, will cause the said strip 23 to be wound thereupon. Sections of the other and superposed strips are torn off as required by means of the knife 14.

It will, therefore, be seen that by means of the above described device a duplicate record of all transactions which are recorded on the superposed strips is retained and rolled up upon the roller 9.

When the strips are exhausted from the roller 5, the cover 15, which may be hinged as at 24, Fig. 2, may be lifted back as indicated in dotted lines, the roller 9 removed upwardly out of the slots 3 and the roller 5 then also removed from these slots. The two sections of the said roller 5 may be then pulled out laterally from the tube 21 and inserted in a new tube upon which a fresh supply of strips has been wound. The

parts may then be replaced by reversing the above described order of procedure.

By providing the thumb pieces 11 and 12, it will be seen that the rollers 5 and 9 may be rotated in either direction for the purpose of correction.

What I claim is:

1. In an autographic register, the combination of a suitable frame; a main feed roller mounted upon said frame; two driving wheels co-axial with and fixed to said roller and upon opposite sides thereof, a storage roller; and two pinions co-axial with the latter, fixed thereto upon opposite sides thereof and resting upon the said driving wheels respectively.

2. In an autographic register, the combination of a frame having two oppositely disposed open-ended parallel slots; a main feed roller having the opposite end-portions of its spindle journaled in the bottom of said slots respectively; two driving wheels fixed to said roller and at opposite sides thereof respectively; and a storage roller having the end portions of its spindle in said slots respectively and provided with two pinions fixed thereto and engaging said wheels respectively.

3. In an autographic register, the combination of a frame having two oppositely disposed open-ended parallel slots; a main feed roller having the opposite end-portions of its spindle journaled in the bottom of said slots respectively; two friction driving wheels fixed to said roller and at opposite sides thereof respectively; and a storage roller having the end-portions of its spindle in said slots respectively and provided with two pinions fixed thereto and resting upon said two wheels respectively.

Signed by me this 21st day of December, 1922.

MURDOCK MACDONALD.
